REFINING OF LUBRICATING OILS AND SIMULTANEOUS REFINING OF GASOLINE TYPE MOTOR FUELS THEREWITH

William E. Forney, Merchantville, N. J., assignor to Cities Service Oil Company, New York, N. Y., a corporation of Pennsylvania

Application January 1, 1942, Serial No. 425,266

15 Claims. (Cl. 196—39)

This invention relates to the refining of lubricants and the simultaneous refining of gasoline type motor fuels therewith.

In the cracking of hydrocarbon oils to make motor fuels, whether the cracking be thermal or catalytic cracking, compounds are formed (usually unsaturated hydrocarbons and hydrocarbon sulfur compounds) which are undesirable in the finished fuel. Such compounds are preferably removed or their chemical composition is changed during their finishing refining treatment so that the gasoline or motor fuel will not cloud or change color while in storage or deposit gum while being used in the engine.

Phosphorus pentoxide has been found to have a catalytic action as well as a chemical combining action with the distillate hydrocarbons. It has also been found that the treatment involves reactions with the saturated as well as the unsaturated hydrocarbons. Some of the polymerization and alkylation compounds are not suitable as constituents of motor fuels on account of their boiling point, chemical reactivity, lead susceptibility and the like, but some of these compounds have been found to have properties that make them desirable as addition agents for lubricating oils. Some polymerization and alkalation products have good solvent properties for gums or resins or oxidation products that form in the lubricating oil while it is in use in an engine. Some hydrocarbon phosphorus products are advantageous for imparting extreme pressure and oiliness properties to lubricating oil.

The phosphorus pentoxide promotes catalytic reactions between the hydrocarbons in lubricating oil stocks, particularly the distillate stocks to carry out alkylation and polymerization. The phosphorus pentoxide also combines with hydrocarbons of the lubricating oil stocks to form phosphorus compounds. The presence of the lower boiling point hydrocarbons in gasoline or pressure distillate with the higher boiling point hydrocarbons of the lubricating oil while in contact with the phosphorus pentoxide also promotes reactions between the hydrocarbons of the lubricating oil and the pressure distillate. The compounds formed by all of these reactions are soluble largely in the lubricating oil and these compounds act as addition agents for modifying the properties of the lubricating oil, particularly its extreme pressure and oiliness properties, and anti-oxidation properties.

The primary object of the present invention is to carry out a combined and simultaneous refining treatment of lubricating oils and motor fuel dis-

tillates to provide lubricating oils and motor fuels having improved and desirable properties.

A large portion of the alkylation, polymerization and phosphorus hydrocarbon products resulting from the treatment of a mixture of lubricating oil and pressure distillate with phosphorus pentoxide is very desirable in the finished lubricating oil, so that the treatment is carried out to hold most of the reaction products in the lubricating oil and to separate them from the motor fuel.

Another object of the invention is to provide a carrier for the phosphorus pentoxide treatment of motor fuel distillates so that the distillate may be brought into intimate and continuous contact with the phosphorus pentoxide.

In accordance with this object, one feature of the invention contemplates the suspension of the phosphorus pentoxide in the lubricating oil in the form of a slurry and the continuous circulation of the slurry through the reaction zone. The phosphorus pentoxide is separated from the motor fuel lubricating oil mixture by settling or filtering. After being washed with straight run naphtha, the phosphorus pentoxide is returned to the process to be again mixed with motor fuel and lubricating oil.

Another object of the invention is the use of a dispersing agent with a finely divided catalyst (P_2O_5) to assist in securing an intimate contact of the catalyst with oils being treated. Preferably said dispersing agent is an absorbent clay which also has clarifying and a catalytic action on the oil being treated.

Another object of the invention is to provide a process of simultaneously finishing a motor fuel gasoline and lubricating oil in a single distillation operation.

The large differences in boiling point between the motor fuel and the lubricating oil permits the motor fuel and lubricating oil to be fully separated from one another and at the same time separated from the undesired reaction products formed in the treatment.

With these and other objects and features in view, the invention consists in the improved method of refining lubricating oil and motor fuel hereinafter described and particularly defined in the appended claims.

The various features of the invention are illustrated in the accompanying drawing which shows diagrammatically a flow diagram illustrating the various steps in the treatment of the lubricating oil and motor fuel.

A lubricating oil to be refined in accordance with the present method preferably should be a

lubricating oil from which has been removed the major portion of asphalt or resinous material that occurs therein. Accordingly the lubricating oil is given a preliminary treatment for the removal of asphalt and resin. To accomplish this, the lubricating oil, which may be either a distillate or a residual cylinder stock, is introduced through a line 10 into a heater 12 where its temperature is raised to approximately 150° F. The oil leaving the heater passes through a line 14 into which is introduced a precipitating solvent—propane—through the line 16. Approximately five volumes of propane are mixed with one volume of lubricating oil. The mixture of oil and propane passes into a mixer 18 where it is thoroughly mixed, and the mixture flows through a line 20 into a settling chamber 22. The oil velocity in the settling chamber 22 is preferably slow so that the asphalt which has been precipitated by the propane will settle to the bottom of the chamber 22. The deasphalted oil leaves the upper portion of the chamber 22 through a line 24 and then passes through a heater 26 where its temperature is preferably raised to approximately 200° F. This heated oil then flows through a line 28 wherein it is mixed with propane introduced through a line 30. The additional propane is preferably measured so that the volume of oil passing out of the line 28 will consist of approximately one volume of oil to ten volumes of propane. This mixture flows into a mixer 32 where it is thoroughly mixed and then flows through a line 34 into a separating chamber 36. The velocity of the oil passing through the separator 36 is preferably slow so that any resin which has been precipitated in the oil can settle to the bottom of the separator. The clean oil rises to the top of the separator and flows out through a line 38 to a stripping still 40 wherein the propane is distilled overhead and separated from the lubricating oil. Steam may be used in the stripper for assisting in the separation of the propane from the lubricating oil. The lubricating oil leaves the bottom of the stripper 40 through a line 42 and passes into a separator 44.

The oil treated as described above will have the major portion of the asphalt and resin separated in the treatment. The above-described process of deasphalting and deresining lubricating oil stocks is more specifically illustrated and described in the patent application of David G. Brandt, Serial Number 369,262 filed December 9, 1940.

Another process of deasphalting and deresining lubricating oil stocks is illustrated and described in an application of Ernest F. Engelke, Serial Number 416,612 filed October 27, 1941. The Engelke process utilizes propane or secondary alcohols together with a dilute caustic soda solution for separating asphalt and resin from the lubricating oil.

The lubricating oil which preferably has been treated to remove the asphalt and resins may advantageously be utilized in the simultaneous refining of motor fuel. To accomplish this, lubricating oil from the separator 44 is introduced through a line 46 into a mixer 48. At the same time gasoline or pressure distillate is introduced into the mixer through a line 50. Into the mixture of lubricating oil and distillate is introduced a mixture of phosphorus pentoxide and clay, through a line 52. This mixture of pressure distillate, lubricating oil, phosphorus pentoxide and clay is thoroughly stirred in the mixer 48 and flows through a line 54 to a pump 56 by which

the oil is circulated through a line 58 to a heater 60. The oil leaving the heater flows through a transfer line 62 into the bottom of a reaction chamber 64. The reaction chamber 64 is preferably provided with a stirrer by which the mixture of oils, clay and phosphorus pentoxide is kept in a uniformly mixed condition so that the entire mixture flows upwardly through the reaction chamber and leaves the top of the reaction chamber through a line 66. This mixture flows into the top of a separator 68 wherein clay and part of the phosphorus pentoxide settles out of the oil mixture and may be removed through line 70. If the clay and phosphorus pentoxide are in sufficiently active condition to be used again this material is pumped by pump 72 through a line 74 and returned to the line 58 to be again circulated through the heater in the furnace 60. If the clay-phosphorus pentoxide mixture is highly exhausted then valves are arranged for the pump 72 to pump the mixture through a line 75 into a filter press 76. The partially clarified oil-phosphorus pentoxide mixture flowing through the separator 68 leaves the separator near the top and flows through a line 78 to the filter press 76. In the filter press the clay and phosphorus pentoxide are separated from the oil mixture which consists of the lubricating oil and gasoline. If the color of the lubricating oil is not what is desired, the oil passing through the filter press flows through a line 80 passing through a cooler 82 into the top of a percolating filter 84 where the oil percolates through a filter clay to secure the desired color, the gasoline being in contact with the lubricating oil passing through the filtering medium. The lubricating oil-gasoline mixture leaving the filter 76 may pass directly into a surge tank 86 or the oil coming through the percolation filter may flow through a line 88 into the surge tank. This oil mixture then passes to pump 90 which forces it through a heater 94 into a bubble cap fractionating tower 96. The fractionating tower 96 is provided preferably with a large number of bubble plates in order to secure the desired fractionation. The end point gasoline passes overhead through a line 98 to a condenser and the condensed gasoline and any uncondensed gases then pass into a separator 102. A reflux return line 104 is connected with the separator 102 by which a part of the gasoline may be returned to the top of the tower to assist in the fractionation. A separating tray 106 is provided near the central portion of the bubble tower by which hydrocarbon fractions which preferably are polymers, together with phosphorus-containing hydrocarbons that are not desirable in the finished gasoline on account of their higher boiling point. This cut of undesired material is drawn off through a line 108 to a cooler 110 and collected in a receiver 112. Part of the distillate from the separator 112 may be returned through a line 114 up to the close proximity of the plate 106 to assist in the fractionation. The material which is preferably removed from the receiver 112 through a line 116 may be utilized in the lubricating oil or may be sent to storage. The finished lubricating oil is removed through the line 118 located in the bottom of the bubble tower and passes through a cooler 120 to storage. A gas or steam stripper and auxiliary heating coil may be used in the bottom of the bubble tower to assist in carrying out the fractionation to remove gasoline and other undesired hydrocarbons.

It may be necessary to have more than one separating tray, such as tray 106, in order to re-

move from the lubricating oil and the gasoline fractions which are not desirable in them.

A portion of the phosphorus pentoxide circulated with the lubricating oil-gasoline mixture through the process is consumed in reacting with the hydrocarbons. The phosphorus pentoxide does not react with a very large volume of the hydrocarbon material. Tests with very large volumes of hydrocarbon material have shown that for the average low-boiling lubricating distillate utilized, less than one per cent by weight of the phosphorus pentoxide used is consumed in the chemical reactions. The phosphorus pentoxide acts predominately as a catalyst for promoting polymerization reactions as well as some alkylation reactions.

The clay used in the process is preferably utilized as a carrier or dispersing agent, to assist in maintaining the phosphorus pentoxide in suspension in the lubricating oil-gasoline mixture. This clay can be ordinary filter clay or fuller's earth, or it may be an acid-treated clay which is commonly known on the market as "Filtrol." Some of the more reactive clays assist in decolorizing and polymerizing hydrocarbons in the lubricating oils as well as in the gasoline. However, the reactivity of the phosphorus pentoxide is depended upon for carrying out the reactions desired in the present process and the clay is used primarily as a dispersing agent. The P_2O_5 can be effectively used in the process without clay but the clay greatly facilitates the separation of the P_2O_5 from the oil and also aids in the revivification of the P_2O_5 .

With some types of pressure distillates and lubricating oil, the amount of polymer, alkylation and other products formed tends to foul the clay and phosphorus pentoxide and it is desirable to revivify the clay and phosphorus pentoxide before returning them to the process. In the drawing, a single filter press is illustrated but preferably two or more filter presses are used in practice so that one filter press may be used for revivifying the clay-phosphorus pentoxide mixture while the other filter presses are used in the filtering operation. To revivify the clay-phosphorus pentoxide mixture a filter press is isolated from the circuit and then a washing solution which is preferably a gasoline or a low boiling hydrocarbon, such as pentane, butane or propane, is forced under pressure through the filter press to remove polymerized and tarry materials that tend to foul the clay-phosphorus pentoxide mixture. The washed filter cake, while still in the filter, is dried by blowing with a stream of inert gas such as flue gas. It may then be removed from the press and broken up and returned in the form of a slurry with pressure distillate through a line 122 to the mixer 48. It is not necessary to form a slurry with the filter cake and this cake may be returned mechanically to the mixer 48 to again make up the slurry mixture.

In the treatment of most mixtures of lubricating oil and pressure distillate it has been found that $\frac{1}{2}$ pound phosphorus pentoxide per barrel of pressure distillate-lubricating oil mixture is sufficient. However, if the hydrocarbons and the lubricating oil-gasoline mixture are such as to utilize a considerable quantity of phosphorus pentoxide, it may be necessary to raise the proportion of phosphorus pentoxide to one pound of phosphorus pentoxide per barrel of lubricating oil-gasoline mixture.

In the preferred treating process, about three parts of clay for one part of phosphorus pentox-

ide will give a satisfactory slurry. This clay, however, may vary from two to five parts of clay for one part of phosphorus pentoxide.

For the treatment of most distillate lubricating oils, particularly the neutrals, three to four volumes of pressure distillate or gasoline is used for each volume of lubricating distillate. When the lubricating oil being treated is a residue oil or cylinder stock then two volumes of gasoline may be used for each volume of lubricating residue.

In carrying out the main treating reaction to promote the polymerization, alkylation and phosphorus combination, the oil is circulated at a pressure of from 250-275 pounds in a continuous circuit and the temperature leaving the furnace 60 and while passing through the reaction chamber 64 and separator 68 varies from 425° F. to 275° F. It is preferred that the transfer temperature of the oil mixture should not rise above 425° and may be as low as 300° F. If the oil leaving the furnace has a temperature of 300° F., the oil leaving the separator 68 will probably be below 200° F.

Reference has been made in the description to the use of pressure distillate. This may also include a fraction of C_3 and C_4 hydrocarbons obtained during the stabilization of cracked gasoline or pressure distillate in the refinery. It is commonly known as stabilizer reflux since it is used for this purpose. This fraction may be used to replace the pressure distillate in whole or in part. If a mixture of C_4 hydrocarbons and C_3 hydrocarbons are utilized in the process then the distillation in the tower 96 will have to be modified to accurately separate these constituents from the lubricating stock.

The preferred form of the invention having been thus described, what is claimed as new is:

1. A method of simultaneously refining motor fuel distillate and lubricating oil comprising intimately mixing a motor fuel distillate containing unsaturated hydrocarbons with a lubricating oil and phosphorus pentoxide, heating the mixture and holding the mixture in intimate contact for an extended period of time to cause the motor fuel distillate and the oil to react with P_2O_5 and allow reaction products to be dissolved in the lubricating oil, separating the phosphorus pentoxide from the oil mixture and fractionating the mixture to separate the motor fuel as an overhead cut and the lubricating oil together with dissolved reaction products as a bottom cut.
2. The method defined in claim 1 in which the mixture of motor fuel-lubricating oil and phosphorus pentoxide advances as a continuous stream through each step of treatment.
3. The method defined in claim 1 in which the phosphorus pentoxide separated from the lubricating oil-motor fuel mixture is again mixed with untreated lubricating oil and motor fuel to be reused in the treatment.
4. The method defined in claim 1 in which phosphorus pentoxide is used in the ratio of $\frac{1}{2}$ to 1 pound per barrel of lubricating oil-motor fuel mixture.
5. The method defined in claim 1 in which the oil mixture is heated to a temperature of 275-425° F.
6. The method defined in claim 1 in which the oil mixture is heated to a temperature of 275-425° F. and is held under a pressure of 250-275 pounds while the products are reacting.
7. The method defined in claim 1 in which two

to four volumes of motor fuel are mixed with one volume of lubricating oil.

8. The method defined in claim 1 in which resinous and asphaltic constituents of the lubricating oil are removed before the lubricating oil is mixed with the phosphorus pentoxide and motor fuel.

9. The method of simultaneously refining motor fuel distillate containing unsaturated hydrocarbons and lubricating oil comprising intimately mixing a motor fuel distillate and a lubricating oil with clay and phosphorus pentoxide, heating the mixture and holding it in a mixed state for an extended period of time to cause the motor fuel distillate and the oil to react with P_2O_5 and allow reaction products to be dissolved in the lubricating oil, separating the clay and phosphorus pentoxide and fractionating the lubricating oil-motor fuel mixture to separate them, said separated lubricating oil retaining dissolved reaction products.

10. The method defined in claim 9 in which undesired polymers and phosphorus compounds are separated from the motor fuel and lubricating oil in the fractional distillation step.

11. The method defined in claim 9 in which

heat treatment of the lubricating oil-motor fuel mixture is carried out under pressure of from 250-275 pounds.

12. The method defined in claim 9 in which the heat treatment of the lubricating oil-motor fuel mixture is carried out under a pressure of 250-275 pounds and at temperatures which may vary from 274-425° F.

13. The method defined in claim 9 in which the phosphorus pentoxide is used in the ratio of $\frac{1}{2}$ to 1 pound of phosphorus pentoxide per barrel of lubricating oil-motor fuel mixture and approximately 3 parts of clay is used for each part of phosphorus pentoxide.

14. The method defined in claim 9 in which the phosphorus pentoxide and clay are separated by filtration and then revivified by washing with light oil whereon they are prepared to be returned into the treating method for reuse.

15. The method defined in claim 9 in which resinous and asphalt constituents of lubricating oil are substantially removed before the lubricating oil is mixed with the motor fuel and phosphorus pentoxide.
